UNITED STATES PATENT OFFICE.

JOSEPH H. WHITTINGTON, OF BUFFALO, NEW YORK, ASSIGNOR TO THE NEW YORK SUPPLY COMPANY, OF BUFFALO, NEW YORK, A FIRM.

RIBBON AND STOCK SUPPORTER.

SPECIFICATION forming part of Letters Patent No. 707,479, dated August 19, 1902.

Application filed December 10, 1901. Serial No. 85,406. (No model.)

To all whom it may concern:

Be it known that I, JOSEPH H. WHITTINGTON, a citizen of the United States, residing at Buffalo, in the county of Erie and State of New York, have invented certain new and useful Improvements in Ribbon and Stock Supporters, of which the following is a specification.

This invention relates to an improved means for holding a ribbon, stock, or the like in place around the neck of a person; and it consists of a back member and a front member which are adapted to be attached to a dress or shirt and have a plurality of retaining extensions between which the ribbon, stock, or the like is supported, each member being formed in one integral piece.

The object of the invention is to support and retain the stock, ribbon, or the like in proper position on the neck and also attach it to the dress or shirt, all of which will be fully and clearly hereinafter described and claimed, reference being had to the accompanying drawings, in which—

Figure 1 represents a detached plan view of the back member. Fig. 2 is a detached plan view of the front member. Fig. 3 is a top view of the two members in proper position with the arrangement of the ribbon, stock, or the like shown in dotted lines.

In referring to the drawings in detail, in which a preferred adaptation of the invention is shown, like numerals designate like parts.

The back member A is formed in one integral piece, as shown in Fig. 1, having a body portion 1, provided with a buttonhole 2, which is adapted to engage the rear button on a shirt or dress, and two upwardly-extending retaining-fingers 3, which are separated from each other by a deep depression or slot 4 for the passage of the ribbon, stock, or the like. The front member B is also formed in one integral piece and has a body portion 5, provided with a buttonhole 6, adapted to button over the front button in a shirt or dress, and three downwardly-extending retaining-fingers 7, separated from each other by depressions or slots 8, between which the ribbon, stock, or the like is adapted to pass. The members are preferably made of celluloid,

paper, or similar material. The member A may be provided with two parallel vertical slits 9, extending up from the lower edge on opposite sides of the buttonhole 2, which divide the lower portion of the member into three separate parts, two of which can be placed on one side and one on the other of the band of the garment to more firmly support the member therefrom and prevent turning or twisting of the member on the collar-button to which it is attached. In arranging a ribbon, stock, or other article of adornment in place with this improvement the back and front members are buttoned in place, the member A, if slotted, as described, straddling the band of the garment. One end of the article is passed through the depressions or slots 8 in the front member B, as shown at 10 in Fig. 3. It is then looped half-way around the neck and passed through the depression or slot 4 in the back member, as shown at 11, and finally wrapped or looped one and one-half times around the neck and members, as at 12 in Fig. 3, thereby concealing the members from view and forming an unwrinkled neck-adornment. The two ends 13 and 14 are tied in a bow-knot or secured in any suitable manner. The end 13, projecting beyond the portion 10, which passes through depressions or slots, is drawn beneath the outer loops 12, thereby forming a firm support for the knot when tied. As each of the members is in one piece, they are stamped or cut out complete at one operation.

The advantages of this invention are that the ribbon, stock, or other article is held down in front and up in the rear, that it presents an unwrinkled appearance when in place on the neck of the wearer, that it is easily and quickly put on or taken off, and that while the article is retained in place and cannot be detached the retaining-fingers will permit a slight movement of the article independent of the garment while bending or turning the neck.

I claim as my invention—

1. An improved means for holding a ribbon, stock, or other article in place around the neck of a person, comprising a back member and a front member, each formed in one

integral piece and having a plurality of retaining-fingers separated by slots through which the ribbon or other article is adapted to be passed, substantially as set forth.

- 5 2. An improved means for holding a ribbon, stock or other articles in place around the neck of a person, comprising a back member formed in one piece and having a body portion provided with a buttonhole adapted to 10 engage the rear button of a garment and upwardly-extending fingers between which the ribbon or other article is adapted to be passed, and a front member formed in one piece provided with a buttonhole adapted to engage 15 the front button of a garment and downwardly-extending fingers between which the

ribbon or other article is adapted to be passed, substantially as set forth.

3. An improved means for holding a ribbon, stock, or other article in place around 20 the neck of a person, comprising a back member and a front member, each having a plurality of retaining-fingers separated by slots through which the ribbon or other article is adapted to be passed, and one of said members having slits through which the band of the garment is adapted to pass, substantially as set forth.

JOSEPH H. WHITTINGTON.
